TUNABLE HIGH-FREQUENCY TANK
CIRCUITS

Walter van B. Roberts and Samuel G. Frantz,
Princeton, N. J., assignors to Radio Corporation
of America, a corporation of Delaware

Application January 22, 1943, Serial No. 473,196

11. Claims. (Cl. 178—44)

1

The present invention relates to tuned circuits and, more particularly, to high frequency tanks in the form of resonant chambers. It is known that at ultra high frequencies a tuned circuit, including a conventional coil and condenser, has a comparatively low factor of merit or "Q." In order to obtain an improved factor of merit a structure in the form of a single turn toroid winding with the tuning capacity in the form of flat plates at the center of the toroid may be used. With certain proportions of the structure as related to the wavelength the resonance rise, or "Q," or factor of merit of such a combination may easily attain a magnitude of several thousand. The formula for computing this factor is

$$Q_{\text{optimum}} = 89R\sqrt{F}$$

where R is the radius of revolution of the torus in centimeters and F is the frequency in megacycles. The radius r of the generating circle of the torus must be equal to .707 R for the above equation to hold. This relation was given by H. G. Clavier in "Communications" magazine, September 1942. It will be noted that it is desirable to make the resonant structure quite large but practical considerations usually place a limit on size.

An object of the present invention is the construction of a high "Q" tank circuit which is readily tunable.

A further object of the present invention is the provision of stable adjusting means for tuning a toroidal, resonant circuit for high frequencies.

Still a further object of the present invention is the provision of easily adjusted means for tuning a toroidal tank circuit.

Still a further object of the present invention is the provision of a high "Q" tank circuit which may be easily constructed.

Still a further object of the present invention is the provision of a high frequency tank circuit which may be designed to respond in a predetermined manner to certain variations in meteorological conductions, such as temperature or pressure.

The foregoing objects, and others which may appear from the following detailed description, are attained by providing a tank circuit in the form of a conductive walled chamber having characteristics such that the spacing between a pair of opposing walls determines the resonant frequency. The spacing is adjusted by providing a conductive rod between the walls for pulling them together or forcing them apart. The length of the rod is so chosen that it has a very small effective conductance at the operating frequency. Specifically, the tank circuit may be a single turn toroidal winding having a tuning capacity in the form of a flat plate at the center of the toroid. Extending through the center of the flat plates

2

is a rod having such length as to present a relatively high inductance to the waves within the resonant chamber, said rod being threaded at its ends and arranged to vary the spacing between the plates as a result of its rotation.

5 The present invention also contemplates hermetically sealing the resonant chamber, as described above, so that its dimensions will change in a predetermined manner with variation in atmospheric pressure. Alternatively, the tuning structure may be so constructed as to have an extremely high coefficient of expansion with temperature changes so that an enormously increased variation in frequency is attained for moderate variations in temperature.

10 15 The novel features which, it is believed, are characteristic of the present invention are pointed out with particularity in the appended claims. The invention will, however, be more completely understood by reference to the following detailed description, which is accompanied by a drawing in which Figure 1 illustrates in perspective, and partly in section, a high frequency tank circuit of a type to which the present invention may be applied; Figure 2 shows, likewise in perspective and partly in section, the application of the present invention to the tank circuit of Figure 1, while Figure 3 illustrates a modification of the form of the invention shown in Figure 2.

20 25 30 The high frequency tank circuit of Figure 1 includes an inductance in the form of a single toroidal chamber 5 having an annular slit 6 along the inner surface of the torus. Across the edges of the slit 6 are connected a pair of circular plates 8 and 9 providing a tuning capacity for the tank circuit, the inductance being provided by the interior circumferential length of chamber 5 between one edge of slit 6 and the other edge. Energy is applied to or abstracted from the tank circuit by means of transmission line TL, shown in this figure as including a pair of parallel conductors 10 and 11. The conductors 10 and 11 terminate within the interior of the torus in a coupling loop 12, the dimensions of which may be adjusted, as desired, to vary the coupling between the transmission line and the resonant circuit. The conductors of the transmission line may pass through apertures in the wall of the chamber or the apertures may be sealed by insulators 13 if 35 40 45 50 it is desired to make the tank circuit airtight.

55 As mentioned above, the resonant frequency of the tank circuit is altered within certain limits by varying the spacing between capacity plates 8 and 9. Heretofore, the most practicable way of doing this has been to provide a clamping structure, such as C clamp 15 having an adjusting screw 16 for pressing plates 8 and 9 closer together or allowing them to spring further apart due to the spring action of the toroidal portion 5. A practical objection exists to this method of

tuning in that the relatively long dimensions of C clamp 15 are likely to be considerably varied by temperature variations unless the entire C clamp is made of a material which is substantially non-temperature responsive. However, such materials are relatively expensive and large quantities are necessary due to the size of clamp 15.

In accordance with the present invention, as shown in Figure 2, an improved means is provided for adjusting the spacing between plates 8 and 9. The plates are made of thick material so as to be relatively free of microphonic vibration and are squeezed together by rod 18 passing through the space between plates 8 and 9. In order that rod 18 does not act as a short circuit on the tank its length must be made long enough to have considerable inductance. Therefore, pipes 19 and 20, each closed at one end and attached at the other end to plates 8 and 9, respectively, are provided and concentrically arranged with respect to rod 18. The closed ends of pipes 19 and 20 are threaded to engage with threaded portions 22 and 23 of rod 18. It is contemplated as being within the scope of the present invention to make each of the pipes 19 and 20 equal in length to substantially one quarter of the mean operating wavelength of the system so that only a very small effective conductance is shunted across between plates 8 and 9. Thus substantially no energy is absorbed by the adjusting means for tuning the tank. The rod 18, together with the surrounding pipes 19 and 20 will preferably, in this form of the present invention, be adapted to have substantially zero temperature coefficients. For example, they may be made of steel which has substantially a zero temperature coefficient and is silvered or gold-plated in order to provide greater conductivity on the current carrying surfaces.

The threaded portions 22 and 23 of rod 18 may be threaded in opposite directions as is done in turnbuckle construction if only coarse frequency adjustment is desired. However, if it is desired to obtain a very fine adjustment of the operating frequency of the tank circuit the threads 22 and 23 are preferably cut in the same direction but with slightly different pitches so that several turns of rod 18 are required to produce a very small change in the separation between plates 8 and 9. A suitable dial and knob arrangement 24 may be provided at one end of rod 18 for the purpose of recording the adjustment of the tank circuit. This dial arrangement may be a more or less conventional tuning dial arrangement or it may be constructed in the form of a micrometer head. A coupling to the tank circuit of Figure 2 is provided by means of loop 12 connected to transmission line TL as in the case of Figure 1. However, if desired, an additional or alternate coupling may be obtained by tapping conductor 26 of a coaxial transmission line CTL to a desired point along rod 18. Impedance matching is provided by varying the point of contact of conductor 26 with rod 18.

The modification of the present invention shown in Figure 3 is similar in operation to that shown in Figure 2 but the structure is more adaptable to construction by a spinning process. For convenience in construction the tank is divided laterally into two shell-like halves 30 and 31. Each of the halves may be separately spun and then assembled and soldered together, as indicated by the solder joint 33. The pipes 19 and 20 of Figure 2 are replaced by somewhat hemispherical portions 32, 34 in Figure 3. Thus

each half may be spun from a single sheet of metal. The only joint in the structure is the solder joint 33 around the circumference of the device. The details of operation of the tuning means 18 is the same as described with reference to Figure 2.

In the modifications of the invention shown in Figures 2 and 3, in order to prevent variations in atmospheric pressure from varying the tuning of the tank, a small air leakage should be provided at some point. This may be at the point of insertion of the transmission line, or at some other point. However, advantage may be taken of the effect of variation in atmospheric pressure upon the frequency of the tank for the purpose of measuring elevation by means of sounding balloons. In this case the tank circuit would be employed as the frequency determining element of an oscillator, the input and output circuits of the tube being coupled to the tank by coupling links such as loop 12 and/or tap 26. The coupling links should pass through airtight insulating seals such as insulators 13, 13 of Figure 1. If the tank tuning means is made of zero temperature coefficient material the frequency of the tank will then be a function of atmospheric pressure only and a receiver located on the ground to measure the frequency of oscillations emitted by the transmitter carried by the sounding balloon will obtain therefrom, in conjunction with a calibration, curve, the atmospheric pressure at the location of the balloon. If desired, an additional transmitter using a similar tank circuit as a frequency determining element may be used in which the tuning rod 18 and the pipes 19 and 20 are made of materials having widely different temperature coefficients so that the generating frequency will vary as a function of temperature. Thus a separate receiver located on the ground to measure the frequency of operations emitted from the second oscillator will obtain therefrom, in conjunction with a calibration curve, the atmospheric temperature at the location of the balloon. The second mentioned tank should, of course, not be hermetically sealed as, otherwise, the variation in pressure will also influence the general frequency.

While we have illustrated some specific embodiments of the present invention it should be clearly understood that the invention is not limited thereto since many modifications may be made in the several elements employed and in their arrangement and it is, therefore, contemplated by the appended claims to cover any such modifications as fall within the spirit and scope of the invention.

We claim:

1. A tank circuit including inductance and a pair of plates providing capacity connected across said inductance, and means for varying the spacing between said plates comprising a metallic adjustable spacing bar, said bar being arranged to act as a low loss shunt inductance connected between said plates, said bar being threaded through and in conductive connection with each of said plates.
2. A tank circuit including inductance and a pair of plates providing capacity connected across said inductance, and means for varying the spacing between said plates comprising a metallic adjustable spacing bar, said bar being arranged to act as a low loss shunt inductance connected between said plates, said bar being threaded through and in conductive connection with each

of said plates, the threads being in opposite directions.

3. A tank circuit including inductance and a pair of plates providing capacity connected across said inductance, and means for varying the spacing between said plates comprising a metallic adjustable spacing bar, said bar being arranged to act as a low loss shunt inductance connected between said plates, said bar being threaded through and in conductive connection with each of said plates, the threads being in the same direction and of different pitches.

4. A resonant circuit including a conductive walled resonant chamber, the operating frequency thereof being determined by the spacing between a pair of opposing walls and means for adjusting said spacing including a conductive rod passing through said chamber from one of said walls to the other, the length of said rod being such as to present a high impedance at the operating frequency.

5. A resonant circuit including a conductive walled resonant chamber, the operating frequency thereof being determined by the spacing between a pair of opposing walls and means for adjusting said spacing including a conductive rod passing through said chamber from one of said walls to the other, the length of said rod being such as to present a high impedance at the operating frequency and means for varying the point of attachment of at least one of said walls to said rod.

6. A resonant circuit including a conductive walled resonant chamber, the operating frequency thereof being determined by the spacing between a pair of opposing walls and means for adjusting said spacing including a conductive rod passing through said chamber from one of said walls to the other, the length of said rod being such as to present a high impedance at the operating frequency, said rod being threaded through said walls, the threads passing through said walls being in opposite directions.

7. A resonant circuit including a conductive walled resonant chamber, the operating frequency thereof being determined by the spacing between a pair of opposing walls and means for adjusting said spacing including a conductive rod passing through said chamber from one of said walls to the other, the length of said rod being such as to present a high impedance at the operating frequency said rod being threaded through said walls, the threads being in the same direction but of different pitch.

8. A resonant structure including a pair of complementary circular plates each having a concavity in the center, a flat annular intermediate portion and a semi-circular trough around the edge and means for securing the outer edges of said troughs together to form a toroidal inductance with the flat portions of said plates

cooperating to form a tuning capacity for said inductance, there being threaded apertures at the center of each concavity to accept a threaded rod for adjusting the spacing between the flat portions of said plates.

5 9. A resonant structure including a toroidal conductive structure having an annular slot on the inner surface thereof, flat conductive parallel plates connected to adjacent edges of said slot, each of said plates having a tubular member attached to its midpoint, said tubular members being directed in opposite directions and closed at their opposite ends, and a conductive rod passing through said tubular members from one end to the other and threaded through said closed ends.

10 10. A resonant structure including a toroidal conductive structure having an annular slot on the inner surface thereof, flat conductive parallel plates connected to adjacent edges of said slot, each of said plates having a tubular member attached to its midpoint, said tubular members being directed in opposite directions and closed at their opposite ends, and a conductive rod passing through said tubular members from one end to the other and threaded through said closed ends, the length of said rod being such as to present a high inductance to energy of the operating frequency of said structure.

15 11. A resonant structure including a toroidal conductive structure having an annular slot on the inner surface thereof, flat conductive parallel plates connected to adjacent edges of said slot, each of said plates having a tubular member attached to its midpoint, said tubular members being directed in opposite directions and closed at their opposite ends, and a conductive rod passing through said tubular members from one end to the other and threaded through said closed ends, the length of said rod being such as to present a high inductance to energy of the operating frequency of said structure, each of said tubular members having a length of the order of one quarter of the operating wavelength.
